UNITED STATES PATENT OFFICE.

IRVING N. STEWART, OF PHILADELPHIA, PENNSYLVANIA.

PORTABLE WARDROBE.

1,342,269.

Specification of Letters Patent.

Patented June 1, 1920.

Application filed October 8, 1919. Serial No. 329,275.

To all whom it may concern:

Be it known that I, IRVING N. STEWART, a citizen of the United States, residing in Philadelphia, Pennsylvania, have invented 5 the Portable Wardrobe, of which the following is a specification.

This invention relates to wardrobes and like cabinets, and the object of the invention is to provide a wardrobe which may be collapsed to minimum proportions and which 10 is so light of weight as to make it thoroughly portable.

In the attached drawings:

Figure 1 is a view in perspective of the 15 wardrobe set up and with the doors open to show the details of the construction;

Fig. 2 is a horizontal section of the wardrobe; and

Fig. 3 is a perspective of the wardrobe 20 folded.

With reference to the drawings, the wardrobe comprises two side panels, 1 and 2, connected at or near their tops and bottoms by means of top and floor members, 3 and 4 respectively. The floor member 4 consists of two equal panels, 4^a and 4^b, said panels being connected at their outer edges to the side panels 1 and 2 respectively by means of hinges 4^c located on the inside of the 25 wardrobe, and the two floor panels, 4^a and 4^b, being connected at their adjoining edges by hinges 4^d located upon the underside of the floor and on the outside of the wardrobe. A bolt, 5, or the like, is provided upon the 30 inside of the floor, 4, said bolt extending across the joint of the panels 4^a and 4^b to reinforce the hinges 4^d in supporting the floor at its center and to make it more rigid.

The top, 3, of the wardrobe consists of 35 two equal panels 3^a and 3^b, said panels being connected at their outer edges to the side panels 1 and 2 respectively by means of hinges, not shown in the drawings, said hinges corresponding to the hinges 4^c upon 40 the floor panels and being located upon the underside of the said top panels and upon the inside of the wardrobe. The top panels, 3^a and 3^b, are connected at their adjoining edges by hinges 3^d, said hinges being located 45 upon the upper surface of the top as clearly shown in the drawings. A bolt, 6, or the like, extends between the top panels upon the inside of the wardrobe and prevents 50 sagging of the top.

Extending between the side panels, 1 and 55 2, near the top thereof is a shelf member, 7, said shelf being attached in the present instance to the side panel, 1, by hinges (not shown) located upon the underside of said shelf. At the opposite side, the shelf is detachably secured to the side panel, 2, by a hook, 7^a, and is supported by bolts, 7^b, secured to the underside of the shelf, said bolts entering keepers, 7^c, carried upon the inside of the panel 2. 60

Hinged to the side panel, 1, at one corner of the wardrobe is a door, 8, and a similar door, 9, is hinged to the side panel, 2, at the diagonally opposite corner of the wardrobe. The hinges, 10, which connect these doors to 70 the panels are of the double action type, and permit the doors being folded back against the sides of the panels, as illustrated in Fig. 3.

In folding the wardrobe, the hook 7^a attached to the shelf, 7, is released, the bolts 7^b withdrawn, and the shelf 7 lowered to the position, shown in Fig. 3, in which it is suspended from the hinges attaching it to the side panel 1. The doors 8 and 9 are 75 then folded back against the panels 1 and 2 respectively, the bolts 5 and 6 released and the two side panels 1 and 2, forced inwardly together, the top dropping inwardly where the panels 3^a and 3^b adjoin, and the floor also 80 folding inwardly at the center where the two panels 4^a and 4^b meet. The various parts of the wardrobe eventually assume the 85 positions shown in Fig. 3, and may be retained so by any suitable means, as for instance, a hook 11, extending between the side panels 1 and 2.

A cabinet or wardrobe constructed upon the principles herein disclosed finds a particular application to apartments and the 95 like in which it is necessary to take advantage of every possible foot of floor space and in which there is little or no closet space. A wardrobe of this type, being extremely portable, may be moved at will to the part 100 of the house which is best adapted to receive it, and may be folded to negligible proportions when extra floor space may be required.

I claim:

A wardrobe having side panels, roof and bottom panels, said roof and bottom panels being formed in two equal sections hinged

together at their abutting edges and each hinged at its opposite edge to one of the side panels, releasable supporting means disposed at the point of abutment of the sections, a shelf disposed within the wardrobe, said shelf being hinged to one of the side panels and detachably connectible to the

other side panel, and two doors each hinged to a side panel at diagonally opposite corners of the wardrobe, the whole forming a 10 structure adapted to be collapsed into a substantially flat unit when not in use.

IRVING N. STEWART.
